CLAIM

The ornamental design for a security fence panel, as shown and described.

DESCRIPTION

FIG. 1 is a perspective view of a security fence panel showing our new design;

FIG. 2 is a front perspective view thereof;

FIG. 3 is a front elevational view thereof;

FIG. 4 is a rear view thereof;

FIG. 5 is a top view with the bottom view being a mirror image thereof;

FIG. 6 is a left side view thereof; and,

FIG. 7 is a right side view.

The broken lines showing the wall and a gate there-through are for illustrative purposes only and form no part of the claimed design.

FIG. 4

FIG. 3

FIG. 2

FIG. 7

FIG. 6

FIG. 5
